BACKREST SUPPORT

Charles E. Corchran, Lake Hubert, Minn., assignor to Variety Products Inc., Waseca, Minn.

Filed Apr. 12, 1971, Ser. No. 133,483

Term of patent 14 years

Int. Cl. D6—99

U.S. Cl. D6—197

FIG. 1 is a front perspective view of a backrest support showing my design;

FIG. 2 is a rear perspective view;

FIG. 3 is a front elevational view;

FIG. 4 is a side elevational view;

FIG. 5 is a sectional view taken along the lines 5—5 of FIG. 3; and

FIG. 6 is a sectional view taken along the lines 6—6 of FIG. 3.

I claim:

The ornamental design of a backrest support, substantially as shown.
